UNITED STATES PATENT OFFICE

LAZRUS WITKOWSKY, OF NEW YORK, N. Y.

VEST.

SPECIFICATION forming part of Letters Patent No. 248,244, dated October 11, 1881.

Application filed August 11, 1881. (No model.)

To all whom it may concern:

Be it known that I, LAZRUS WITKOWSKY, a citizen of the United States, residing at New York, in the county and State of New York, 5 have invented new and useful Improvements in Garments, of which the following is a specification.

This invention consists in the combination, with a waistcoat, of two stiffening-strips and 10 two suspender-straps secured to said stiffening-strips, so that by the suspender-straps the pantaloons can be supported, and at the same time, by means of said stiffening-strips, a firm connection is obtained for the suspender-straps.

15 With the waistcoat and the suspender-straps secured thereto are combined two buckles secured in pockets formed in the pantaloons.

This invention is illustrated in the accompanying drawings, in which Figure 1 represents 20 a sectional side view of a waistcoat and pantaloons connected according to my invention. Fig. 2 is a sectional inside view of a waistcoat on a larger scale than the previous figure. Fig. 3 is a transverse section of the same in the plane 25 xx , Fig. 2. Fig. 4 is a side view of the pantaloons.

Similar letters indicate corresponding parts.

In this drawing the letter A designates a waistcoat which is provided with two suspender-straps, B. These suspender-straps are connected to stiffening-strips C, which are secured in the waistcoat, one beneath each of the arm-holes a. Said stiffening-strips are, by preference, made of spring-steel, and each of them 35 is provided with an eye, b, which projects through the lining of the waistcoat and serves to support a ring, c, to which the suspender-strap is connected by a snap-hook, d. The stiffening-strips decrease in thickness from the top 40 downward, so that their lower ends will readily yield and conform to the shape of the body of the person wearing the waistcoat.

By these means a firm and durable connection is obtained between the waistcoat and the 45 suspender-straps, and if these straps are attached to the pantaloons the strain of the latter is brought to bear upon the shoulders of the person wearing the waistcoat, and by the stiffening-strips the waistcoat is prevented from

being thrown out of shape by the strain of the 50 pantaloons.

The connection between the pantaloons D and the waistcoat A is effected by means of buckles e, which are secured in pockets f, formed in the sides of the pantaloons, said buckles being fastened to straps g, which extend down on the inside of said pockets, and are firmly attached thereto by stitching or otherwise.

55 The suspender-straps are provided with a series of holes, h, so that they can be adjusted 60 in the buckles e, to suit the length of the pantaloons.

Heretofore a yoke has been attached between the external and internal parts of a vest, said yoke being forked, and extending from a 65 point at or near the center of the back over the shoulders and down the front sides of the vest, the front and rear ends being furnished with rings, from which the pantaloons may be suspended. Such, however, is not my invention, 70 and is not claimed by me.

What I claim as new, and desire to secure by Letters Patent, is—

1. The combination, substantially as herein-before described, of a waistcoat, two stiffening-strips fastened in said waistcoat, and two suspender-straps attached to the upper portions of the stiffening-strips and adapted to adjustably connect with buckles on the pantaloons.

75 2. The combination, substantially as herein-before described, of a waistcoat, two stiffening-strips fastened in said waistcoat, eyes b, secured to the stiffening-strips, rings c, secured in these eyes, and suspender-straps attached to and suspended from the rings.

80 3. The combination, substantially as herein-before described, of a waistcoat, two stiffening-strips fastened in said waistcoat, two suspender-straps attached to the stiffening-strips, and buckles e, secured to the pantaloons D.

85 90 In testimony whereof I have hereunto set my hand and seal in the presence of two subscribing witnesses.

LAZRUS WITKOWSKY. [L. S.]
